GEORGE H. LEWIS, OF CHICOPEE FALLS, MASSACHUSETTS, ASSIGNOR TO THE FISK RUBBER COMPANY, OF CHICOPEE FALLS, MASSACHUSETTS, A CORPORATION OF MASSACHUSETTS.

ADJUSTABLE DIE.

1,252,821.

Specification of Letters Patent.

Patented Jan. 8, 1918.

Application filed July 14, 1917. Serial No. 180,604.

To all whom it may concern:

Be it known that I, GEORGE H. LEWIS, a citizen of the United States of America, residing at Chicopee Falls, in the county of 5 Hampden and State of Massachusetts, have invented certain new and useful Improvements in Adjustable Dies, of which the following is a specification.

This invention relates to improvements in 10 adjustable dies, and while the invention is capable of general application, it finds one advantageous use in the die heads of tubing machines, such, for example, as are used in the rubber industry for forming continuous 15 tubes and strips of rubber of various cross sectional shapes and sizes.

In dealing with plastic and elastic material, such as rubber, for example, in die forming operations, special problems arise 20 due to the peculiar physical properties of the material. More particularly, by reason of the elasticity of the material, the article formed by the die may be larger than the die opening itself, due to the outward spring or 25 swellage of the material after leaving the confines of the die. Succeeding batches of material are seldom uniform in elastic qualities, and it will, therefore, be apparent that unless some means are provided to compensate 30 for varying degrees of elasticity, a product, non-uniform in size, may be obtained. This invention is concerned, among other things with the provision of a die head, wherein compensatory adjustments 35 may be made from time to time as necessitated by varying conditions in the material being handled or in the character of the work.

One object of the invention is to provide 40 an improved die head, particularly adapted for use with plastic and elastic materials, wherein means are provided to adjust the die to compensate for variations in the elasticity of the material being handled, so that 45 the product formed may be maintained substantially uniform as to size, despite the use of material of varying characteristics.

Another object of the invention is to provide 50 a die head wherein the size and shape of the die opening may be varied in an improved manner, the construction being characterized by a flexible and adjustable arrangement whereby the die is adapted for a wide range of work of varying character.

55 Another object of the invention is to pro-

vide in a die, means whereby the convergent choke passage leading to the die opening may be conveniently varied in respect to its degree of convergence, to control the flow of material to the die opening.

Other objects and advantages will appear in the following description and will be pointed out in the appended claims.

The invention, in an embodiment at present preferred, is shown for illustrative purposes in the accompanying drawings; in which:

Figure 1 is a front elevational view, with parts broken away, of a die head embodying the invention;

Fig. 2 is a sectional elevation thereof taken on the line 2—2 of Fig. 1;

Fig. 3 is a perspective view of one of the former strips used in the die head;

Fig. 4 is a perspective view of one of the 75 filler plates used in the die head; and

Fig. 5 is a perspective view of a pattern for use in conveniently assembling the former strips in the die head to obtain a die opening of the desired size and shape.

The invention will be described herein in merely one of its specific uses; namely, as adapted for use in the die head of a tubing machine. The invention is, however, capable of other uses and the adaptation to be described is given merely for the purposes of illustration.

The tubing machine has not been illustrated in the drawings, since it is unnecessary to an understanding of the invention. 90 The description of the die head as adapted for attachment to the outlet end of a tubing machine will sufficiently disclose the invention since tubing machines are now well known in the art.

Referring to the drawings; A represents a tubular male threaded portion adapted for connection to the outlet end of a tubing machine or any other suitable machine, the only essential of such a machine being a 100 means for forcing material, such as rubber stock for example, into and through the tubular member A. The latter is provided with a square head or flange 6 to the upper and lower edges of which top and bottom 105 plates 7 and 8, respectively, are suitably secured, as indicated in Fig. 2. Side plates 9, formed integrally with a front plate 10, are secured to the side edges of flange 6 and coöperate with plates 7 and 8 to form 11

a hollow boxlike inclosure forwardly of the tubular member A. The front plate 10, however, is only substantially half as high as the inclosure itself so that a relatively 5 large opening is formed in the front wall of the die head. Of course, it is obvious that this front plate as well as other parts may be made of different shapes so that the die opening will be made up under the invention 10 according to the requirements of the product desired.

Secured to the side plates 9 and extending therebetween in spaced parallel relation across the space above plate 10 are cross 15 bars 11. Behind the latter are a plurality of very thin flat strips 12, which are arranged to close the opening between the top plate 7 and the upper edge 13 of front plate 10, except for a small outlet opening 20 14. The strips 12 are each substantially equal in width to the thickness of front plate 10, and bear against and are backed up by a series of filler plates 16, to be later described, which plates are inserted between 25 the rear edges of strips 12 and the front face 17 of the described flanged head 6, as clearly shown in Fig. 2. The plates 16 and the strips 12 may be clamped together by the bars 11 and their securing bolts in an 30 obvious manner. The strips 12 may be also forced together laterally by thrust plates 18, one on each side of the assembled group of strips, as shown in Fig. 1, and suitable bolts 19.

35 The thin strips 12, together with edge 13 of plate 10, or in place of plate 10 a second series of like strips similarly mounted and held as described, permit the convenient formation of the described die opening 14 and permit its size and shape to be conveniently and expeditiously varied, as desired, or as made necessary on account of varying kinds of work or varying conditions in the same kind of work.

40 45 The die opening 14 in the example shown may be formed in the following manner. A pattern *p* (Fig. 5) of suitable material, is formed in the shape and size of the opening desired. Pattern *p* is then laid upon 50 the surface 13 and thereafter the strips 12 are inserted behind bars 11 with their lower ends resting upon the pattern. The bolts 19 and the securing bolts for bars 11 are then tightened to clamp the strips against 55 the filler plates 16 and between the thrust plates 18. The pattern *p* is then withdrawn leaving an opening 14 of the desired shape and size. It is to be noted that the strips, since they are very thin, readily follow 60 curved surfaces of the pattern and closely conform thereto, so that only slight score marks are formed on the curved portions of the strip formed by the opening 14. In practice, I have found that the strips of one 65 thirty-second of an inch may be satisfac-

torily used, although strips of other thicknesses may be used as desired. The score marks formed in the curved portions of the formed strip may, obviously, be reduced to as small a degree as is desired by decreasing 70 the thickness of the strips and all the strips 12 of the group need not be of uniform thickness, as shown, although the illustrated construction is preferable. For example, thick strips may be used for the flat 75 surfaces of pattern *p* and thin strips only for the curved surfaces thereof. It is also to be noted that the size and shape of the opening may be readily varied from time 80 to time, as desired, by simply raising or lowering one or more of the strips 12. The latter may be lowered by hammering on their upper ends and raised by driving upwardly on shoulders 20 formed by notching 85 the strips near their upper ends. The raising and lowering of the strips for small adjustments may be accomplished in the described manner without loosening bars 11 or bolts 19.

90 The filler plates 16, are, in the illustrated embodiment, provided in upper and lower sets, as shown in Fig. 2. Considering either set, the inner end of each strip is beveled toward the rear and concaved laterally, as indicated at 21 in Fig. 4. The concavity of 95 each strip is different, successive strips in a rearwardly direction having a greater degree of concavity than preceding strips. The assembled groups of strips form therebetween a passage 22, technically known as the "choke" of the die head, which passage converges from the tubular member A toward outlet 14 and also changes gradually from an approximately circular cross sectional 100 shape near member A to a flattened substantially elliptical shape adjacent the outlet 14. Other shapes of the choke passage may be made in a similar manner.

105 In each set, the plates 16 are backed up at their outer ends by pivoted thrust plates 23, which are movable inwardly by suitable bolts 24. Each plate 23 is pivoted adjacent the forward end of the die head, the upper plate 23 being connected by pivots 25 with the side plates 9 and the lower plate 23 being fulcrumed on a shoulder 25 (Fig. 2) formed on the front plate 10 near the lower end thereof. It will be readily seen that by turning bolts 24 inwardly the thrust plates may be made to simultaneously force all the plates 16 of their series inwardly. However, by pivoting the thrust plates 23 near the forward end of the die head, each plate 16 of a series is moved varying distances, those plates near the outlet 14 being only slightly moved while those adjacent member A are moved by relatively large distances. By thus moving the plates, the inclination of the walls of the choke passage 110 115 120 125 130 22 may be decreased in a substantially uni-

form manner. The upper set of plates 16 may be held against inward movement by the clamping means described, and the lower set is held against inward movement by 5 gravity action or similar clamping means. The stock forced through passage 22 tends to seat both sets of plates on their members 23.

The adjustment of the choke passage is 10 particularly important and advantageous, where the die is used in the formation of strips of rubber stock, as in tire manufacture, for example. It has been found that with a constant die opening, the strip produced by being forced through the latter, may be varied in size through an appreciable range by increasing or retarding the flow of the stock to the die. The described construction permits convenient acceleration or 15 retardation of the flow to the die opening by moving the filler plates outwardly or inwardly respectively. The adjustable choke opening is most desirable when dealing with plastic material, such as rubber stock, for 20 example. Such material, due to its inherent plasticity and elasticity, tends to spring outwardly after leaving the confines of the die, with the result that the strip formed may be larger than the die opening. This "swell-age" of stock necessarily varies with the 25 properties, particularly the elasticity, of the particular batch of material being handled, and it has been found extremely difficult to make each batch of rubber stock of exactly 30 the same elasticity. The practical difficulties arising from varying qualities of rubber stock have made it expedient to provide compensating means in the die head rather than to attempt precise uniformity of material. It will be obvious that by varying the 35 choke passage 22 and thus varying the flow to the die opening adjustments to compensate for the variations in the natural properties of the material being handled, may be made. The compensating adjustments 40 may also be made by varying the size of the die opening by the convenient means provided.

The invention has been described in a 45 preferred embodiment for the purposes of illustration, but the scope of the invention is more properly defined by the appended claims than by the foregoing description.

What I claim is—

50 1. A die head, comprising, a casing provided with an inlet into which material may be forced and a die opening through which the material may emerge, a group of movable members between the inlet and die 55 opening arranged to form a wall of a converging passage, and means to simultaneously move all said members by varying increments increasing progressively from one end of the group to the other.

60 2. A die for forming plastic material,

comprising, a casing formed with an inlet into which the material may be forced and a die opening through which the material may emerge in finished form, a passage formed between the inlet and die opening 70 having walls inclining from the former to the latter, means to vary the inclination of said walls, and means to vary the size of said opening, all constructed and arranged so that the size of the member formed by the 75 die may be varied by the last-named means or by varying the flow to the die opening by the first-named means, or by both as desired.

3. A die, including in combination, a front 80 wall made up of a plurality of members mounted so that an edge of each forms an increment of a wall of the die opening and determines the shape thereof, and holding means for said members arranged to permit 85 individual adjustment of each, whereby said members may be positioned so that the combined edges of some or all approximate curved surfaces.

4. A die, comprising, a casing, having an 90 open end, a plurality of thin strips stacked in face to face relation to close said open end except for a relatively small opening, means to clamp said strips to the casing, said strips being independently movable to permit die 95 openings of various sizes and shapes to be formed.

5. A die, comprising, a casing having an inlet and a relatively large outlet opening, a plurality of parallel members stacked face to 100 face to close said opening except for a relatively small die outlet, said members being movable independently or in groups to vary the size and shape of the die outlet, and means to clamp the members to the casing. 105

6. A die, comprising, a casing having an inlet opening at one end and a relatively large opening at the other end, a plurality of thin strips stacked face to face across said opening, said plates being movable independently or in groups as desired to co-operate with a fixed part of the casing to form die outlet openings of various shapes and sizes and means to clamp the plates together and to said casing. 110

7. A die, comprising, a casing having inlet and outlet openings, groups of movable members between said outlets, said groups co-operating with one another to form a connecting passage between said openings which 120 converge toward the outlet opening, means to simultaneously move the members of each group by varying increments increasing progressively toward the said outlet, whereby the degree of convergence of said passage 125 may be varied, and means to hold said members in their various positions of adjustment.

8. A die, comprising, a casing having inlet and outlet openings, a plurality of groups 130

- of members arranged within the casing to form walls of a passage which connects said openings and converges toward the outlet opening, said group comprising a plurality 5 of plates stacked in face to face relation, a member for each group overlying the outer ends of all the plates therein and pivoted at one end near the outlet of the casing, means to move said plate on its pivot, and means 10 to hold the plates in their adjusted positions within the casing, all constructed and arranged so that said passage may be adjusted to various degrees of convergence to vary the flow therethrough.

15 9. A die head, comprising, a hollow casing having an inlet at one end and a relatively large opening at the other end, a plurality of movable plates stacked face to face across the opening to close the latter except 20 for an outlet for the die, means to clamp said plates together, a plurality of plates between the first-named plates and a part of said casing, said plates shaped to produce a wall connecting the inlet and outlet 25 and converging toward the latter, means to move the last-named plates by varying increments increasing progressively toward the inlet and means to clamp both groups of plates against said part.

10. A die head, comprising, a casing having a tubular inlet and a hollow rectangular boxlike portion, an elongated die outlet formed in the front wall of said portion, groups of plates stacked face to face within the casing, the inner ends of each group being inclined from the outlet toward the inlet, and the inner ends being laterally concaved to varying degrees so that a convergent passage gradually changing from substantially the shape of the inlet to substantially that of the outlet is provided, and means to simultaneously move all the plates of each group by varying increments increasing progressively from the outlet to the inlet.

11. A die including in combination a front wall made up of laminae, holding means therefor adapted to permit individual adjustment of each lamina, the edges of such laminae being arranged to determine the shape of the die opening, whereby the latter may be changed as desired.
